EYELASH CURLER

Jacob Goodman, Brooklyn, N. Y., assignor to
Delamere Company, Inc., a corporation of Del-
aware

Application May 27, 1933, Serial No. 673,147

3 Claims. (Cl. 132—32)

This invention relates to eyelash curlers.

One object of the invention is to provide a device of simple and inexpensive construction for curling eyelashes.

5 Another object is to provide a device that is easy to manipulate, and may be used without danger of injuring the eyelashes.

With these and other objects in view, the invention comprises the novel features of construction and arrangement of parts hereinafter described, it being understood that various modifications may be made therein without departing from the spirit and scope of the invention.

10 In the accompanying drawing, illustrating a preferred embodiment of the invention:—

Figure 1 is a side elevation of an eyelash curler, with a section of the lower jaw broken away;

Fig. 2 is a top plan view thereof; and

Fig. 3 is a section, in perspective and on an enlarged scale, taken on the line 3—3 of Figure 1.

15 Referring now to the drawing, the device comprises two jaws 1 and 2, both of which are similarly curved lengthwise to correspond substantially to the curvature of the eyelid. The upper jaw 1 is circular or ovate in cross-section, while the lower jaw 2 has a concave channel or groove 3, preferably open at both ends, and into which the lower portion 4 of the upper jaw fits in such manner as to crimp or curl the eyelashes, as seen 20 in Fig. 3.

25 5 and 6 are arms for operating the jaws, which arms are pivotally connected together by means of a pivot pin 7. These arms may either be integral with the jaws or formed of separate parts 30 and secured thereto.

The outer end of each of said arms is preferably bent inwardly in the form of a loop to provide handle portions 8. It is to be noted that, as shown in Figure 1, the curvature of said loops is 35 such that when the jaws are closed, the inner portions 9 of the two loops will substantially abut against each other. This construction acts as a stop to prevent the application of so much pressure on the jaws as might injure the eyelashes or 40 distort the jaws.

The two jaws are movable angularly toward or away from each other about the pin 7 as a pivot. In use, the jaws are opened by separating the handles and in this condition the device is placed

against the eyelid in position to engage the eyelashes between its jaws. The jaws are then closed, gripping the eyelashes and forming a crimp or curl in them.

5 It will be apparent from the foregoing description that my improved device is composed of few parts, and that the construction is so simple that it may readily be made in large quantities at a relatively low cost.

10 I am aware that prior to my invention it has been proposed to provide an eyelash curler having a pair of cooperating jaws one of which is provided with a rubber pad against which the other presses the eyelashes, and having a leverage system for sliding the one jaw vertically in relation to 15 the other. The use of rubber pads is objectionable not only because it increases the cost but because the pads tend to harden and lose their resiliency, thus decreasing the effective life of the device. 20 My improved construction has no sliding parts, and the form and relationship of its members is such that no rubber pads are necessary to curl the eyelashes.

25 What I claim is:—

1. An eyelash curler comprising a pair of pivotally connected crossed handle arms each having a jaw member at one end, said jaw members being curved lengthwise and extending to one side of the handle arms at an angle to the plane thereof.

25 2. An eyelash curler comprising a pair of pivotally connected crossed handle arms each having a jaw member at one end, said jaw members being curved lengthwise and extending to one side of the handle arms at an angle to the plane 30 thereof, one of said jaw members having a channel into which a portion of the other jaw member enters to curl eyelashes therebetween.

3. An eyelash curler comprising a pair of pivotally connected crossed handle arms each having a jaw member at one end, said jaw members being curved lengthwise and extending to one side of the handle arms at an angle to the plane 35 thereof, the upper jaw being ovate in cross-section, and the lower jaw having a concave channel 40 therein into which the lower portion of the upper jaw fits to curl eyelashes therebetween.

45 JACOB GOODMAN.
